UNITED STATES PATENT OFFICE.

FRANK M. FOSTER, OF COLUMBUS, OHIO.

MACHINE FOR CUTTING GREEN CORN FROM THE COB.

Application filed December 29, 1923. Serial No. 683,328.

This invention relates to improvements in machines for cutting green corn from the cob. The objects of the invention are:

- 5 First, to provide an efficient and rapid machine which will cut the body of the kernel substantially of even length without injuring or crushing of the severed portion of the kernels.
- 10 Second, to provide such a machine which will effectively slice the kernels of corn and thereafter separately remove and scrape any pulp or fragments of the kernel from the cob, preserving the same separately.
- 15 Further objects, and objects relating to details and economies of construction and operation will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing, forming a part of this specification, in which:

- Fig. I is a detail side elevation of my improved machine, portions of the supporting frame being broken away.
- 30 Fig. II is a detail front elevation view of the upper portions of the machine taken from the right hand of Fig. I, the leg portion of the frame being broken away.

Fig. III is a plan view of the structure appearing in Figs. I and II.

Fig. IV is an enlarged detail vertical sectional elevation taken on a line corresponding to line 4—4 of Figs. II and III, the knife and scraper supports appearing in full lines.

40 Fig. V is an enlarged detail sectional elevation taken on line 5—5 of Fig. III of the compressor means for holding the spiked feed rolls yieldingly towards each other.

Fig. VI is an enlarged detail sectional view taken on line 6—6 of Figs. III and IV, showing the arrangement and support of the yielding cutter knives.

Fig. VII is a detail sectional view taken on the curved and irregular line 7—7 of Fig. VI of one of the yielding radially disposed knife and guard carrying arms.

50 Fig. VIII is an enlarged detail sectional view taken on line 8—8 of Fig. VII showing

the arrangement and construction of the cutting knife and the adjustable guard for regulating the depth of the cut.

Fig. VIII^A is a modification of the cutter means showing a plurality of cutter knives.

Fig. IX is an enlarged detail sectional view through a scraper and shoe similar to the section appearing in Fig. VIII, but taken on line 9—9 of Fig. X.

Fig. X is an enlarged elevation view of the scraper taken from the right hand of Fig. IX.

Fig. XI is an enlarged detail elevation view of the yielding guides or centering shoes for directing the corn ear to the revolving spiked feed rollers and cutter knives.

Fig. XII is an enlarged sectional view on line 12—12 of Fig. XI, showing the intermeshed segments and their support for insuring the centering of the guiding centering shoes.

Fig. XIII shows a modification of the cutter head of Fig. VI in which six segmental knives are provided with the same style of support, the yielding compression spring seen in Fig. VI being omitted.

In the drawing, the sectional views are taken looking in the direction of the little arrows at the ends of the section lines and similar numerals of reference refer to similar parts throughout the several views.

Considering the numbered parts of the drawing by their numbers, 1 is the general frame work made up of standards and a suitable top frame 2, preferably of angle bars. A feed chute 3 extends to one side of the main frame, being supported by the brace 3'.

An endless conveyor 4 is disposed to traverse the bottom of the feed chute and is supported on suitable rolls 5 and 6, the roll 6 being on the adjustable bracket 7. Tight and loose pulleys 8 with belt shifters 8' are provided for driving the machine.

A sprocket chain 50 extends from the driving shaft to a sprocket wheel 51 for driving the conveyor.

Pairs of spiked feed rollers 9 and 10 are disposed in opposed relation to engage and advance the corn ears, as indicated by the dotted lines in Fig. IV. These are carried on shafts 11 and 12 provided with universal joints 13 and 14 respectively, the same being driven by gears 15 and 16 which intermesh,

all in a suitable train of gears driven from the tight and loose pulley structure 8.

These shafts are held yieldingly towards each other by the springs 11' resting on the upper shaft 11 in each instance, the same being adjusted by the set screw 11'', detailed particularly in Fig. V.

At the delivery end of the feed chute 3 is disposed a pair of centering shoes 17, 18, carried on arms 19, 20, which are pivoted at 21, 22, respectively, on the cross bar 24. These are provided with intermeshing gear segments 19', 20'. An arm 17 extends upwardly at 17' and a spring 23 is provided for tensioning the same connected at its upper end to the upper end of the arm 17' and at its lower end to the cross bar 24.

The centering shoes 17, 18 flare like a funnel to receive the advancing end of the corn ear and, as they are yieldingly held by the spring 23 and the segment gears referred to, the corn is kept in central position as it advances between the said centering shoes.

The first pair of spiked rollers 9 and 10 engages the ear to carry it forward to the cutting knives. A casing 25, trough-like in form, is provided for the support of the parts of the machine. A knife supporting ring 26 is supported on suitable brackets 27 and carries the cutting knives. The cutting knife arms 28 are pivoted to the ring 26 by pivots 29, four of these arms being preferably provided on which are spirally disposed cutter knives 30, each provided with a shank 31 (see Figs. VI, VII and VIII) disposed in a recess 32 and retained in place by cross bolt 32'. The knives are curved to correspond to the contour of a corn ear and interlap so that they slide or move into telescopic relation with each other as they are swung out and in on their respective pivots.

A guard 33 is disposed back of each knife having an angling shoe-like face and a flaring part 33', each guard being provided with a shank 34 disposed on the opposite side of the arm 28 from the shank 31 of the knife and retained in place by the same cross bolt 32'. A slot 35 extending longitudinally of the shank 34 is provided whereby the guard 33 may be adjusted in its relation to the knife 30. This regulates the depth of the cut and enables the knife to cut off a small portion or substantially the entire kernel from the corn ear being cut.

The yielding relation of the knives is secured by the concentric ring 36, which is carried by the outer ends 28' of the pivoted arms 28, these arms being provided with longitudinal slots 28'' in which are disposed pivot blocks 37 on pivot 38 to permit slight radial movement on said rings 36. A plurality of knives 30, 30^A, see Fig. VIII^A, can be disposed upon the support which will slice the kernels into thin slices wherever that may be desired. The knives are all disposed

in oblique relation to the advancing ear of corn to secure a draw cut.

A second ring 26' is provided with precisely the same structure and arms, each arm of which bears a scraper 39 with a shoe 39' carried on suitable shanks 40 retained on the arm 28 by the cross bolt 32'. 41 is a stop secured to the ring 36 at 42 by welding or otherwise.

43 is an adjustable stop limiting the inward throw of the cutter knives by limiting the movement of the ring 36. A spring 44 on rod 45 acting against the adjusting nut 45' holds the cutter knives or the scrapers, when scrapers are employed, to their work, the pressure thereof being adjusted by adjusting the said nut 45'. As appears in Fig. XIII, six of these knives and arms may be very readily disposed in the circle, thereby securing a little more even cutting of the kernels from the corn ear.

In the bottom of the trough-like structure 25 are discharge chutes 46 and 47; the first, 46, for the cut corn; the second, 47, for the scraped corn.

From this description it is very clear that an ear of corn fed into the machine, which may be advanced to position by the conveyor or may be inserted through the centering shoes by hand, will be seized by the spiked rollers and forced straight through the cutting knives, which will be separated to the right position to cut the kernel of corn at the required depth by guides 33 associated with the blades. An even cutting of the kernel is thus secured, no matter what the size of the cob or corn ear, within the limits of the machine. These kernels, cleanly cut, drop down through the first chute 46 and the ears are advanced by the spiked rollers until they pass under the shoe of the scraper, the scrapers being preferably held strongly against the ears so that they force out all of the remaining pulp, leaving the cob clean of all the kernel. This scraped corn pulp is dropped through the chute 47.

While my machine is intended especially to secure properly the entire cut kernel which makes a very attractive appearance in the can and when separated from the pulp, the machine is especially well adapted to merely cutting off the tips of the kernel and scraping out the contents, delivering it, minus the outer tough covering, through the second chute 47. The lightly cut-off portions are delivered through the first chute 46 and separately canned. However, in view of their being cut very small, they may be introduced into the can with the pulp itself.

My machine is capable of great variations in detail without departing from my invention. I desire to claim it specifically and broadly, and also the parts thereof, as pointed out in the appended claims.

Having thus described my invention what I claim as new and desire to secure by Letters Patent is:

1. In a corn cutting machine, the combination with suitable framework, a ring supported by suitable brackets on the frame of said machine axially disposed to the line of feed, curved radially disposed arms pivoted to said ring, overlapping bevelled and angularly arranged knives disposed centrally and spirally of said ring, the edges of the knives being parallel with the periphery of said ring and overlapping and telescoping one upon the other, radial shanks on the said knives secured to the inner ends of said radially disposed pivoted arms, adjustable bevelled guards with shanks parallel with the knife shanks carried on the opposite sides of said curved arms, a surrounding ring around the said supporting ring, radially projecting portions from the said radially disposed arms with longitudinal slots therein, pivotal blocks on said ring for adjusting and varying the angle of the arms and to control the position of the knives, flexible yielding means between said rings for holding the said knives yieldingly towards the center, a scraper means disposed to act on the ear after the scrapers comprising a second ring with like radially disposed arms and yielding supporting means for the same, scrapers carried by said arms, flaring shoes cooperating with the said scrapers to insure the proper engagement of the scraper with the corn ear, coacting as specified. 45
2. In a corn cutting machine, the combination with suitable framework, a ring supported by suitable brackets on the frame of said machine axially disposed to the line of feed, curved radially disposed arms pivoted to said ring, overlapping bevelled and angularly arranged knives disposed centrally and spirally of said ring, the edges of the knives being parallel with the periphery of said ring and overlapping and telescoping one upon the other, radial shanks on the said knives secured to the inner ends of said radially disposed pivoted arms, a surrounding ring around the said supporting ring, radially projecting portions from the said radially disposed arms with longitudinal slots therein, pivotal blocks on said ring for adjusting and varying the angle of the arms and to control the position of the knives, flexible yielding means between said rings for holding the said knives yieldingly towards the center, coacting as specified. 50
3. In a corn cutting machine, the combination with suitable framework, yielding centering guides to receive the corn ear end 60 on comprising concentrically bevelled side portion, arms for said guides disposed at right angles to the axis thereof, separate pivots for said arms parallel to said axis, intermeshed toothed segments carried by 65 said arms for controlling them to a proper centering movement, and a spring for one of said arms, coacting as specified.
4. In a corn cutting machine, the combination with suitable framework, guiding 70 and feeding means for the corn ear, a set of curved knives disposed in interlapping circular spiral relation for cutting the corn with a draw cut as the ears advance axially therethrough, a set of curved scrapers 75 disposed in circular relation spaced from the said knives for scraping the ear after the cutting knives have acted thereon with separate chutes for the cut and scraped corn, to collect the cut and scraped corn separately. 80

In witness whereof, I have hereunto set my hand.

FRANK M. FOSTER.
